UNITED STATES PATENT OFFICE

JOSEPH WOOLF, OF SAN FRANCISCO, CALIFORNIA

REFRIGERATOR SHOW CASE

Application filed May 5, 1930. Serial No. 448,870.

My invention relates to improvements in refrigerator show cases for butcher shops and the like wherein perishable products may be effectually displayed in an atmosphere cooled by the circulation of air within the case past a refrigerated brine tank mounted longitudinally within the case.

The primary object of my invention is to provide an improved refrigerating show case.

Another object is to provide an improved show case having refrigerating means mounted longitudinally within the back of the case whereby products may be effectually displayed throughout the full length of the case and the temperature maintained at desired degrees.

A further object is to provide an improved device of the character described having means for regulating the circulation of air within the case.

Another object is to provide an improved refrigerating show case wherein a longitudinally disposed brine tank is provided with a refrigerating coil extending longitudinally of the tank and having progressively increasing numbers of turns toward the delivery end of the coil whereby a uniform cooling may be obtained along the entire length of the tank and the case.

A further object is to provide an improved refrigerating device having flues extending transversely through a brine tank for circulating air therethrough, and also provided with shutters operable to regulate the flow of air through the flues.

A further object is to provide an improved case of the character described wherein products to be displayed are supported in spaced relation to the bottom and walls of the case to permit free circulation of air under and around said products.

A further object is to provide an improved device wherein the refrigerating means are effectually concealed to provide a maximum area of unobstructed display space and in which ready access may be had to said refrigerating means for cleaning, repair, or adjustment.

A still further object is to provide an im-

proved show case of simple, compact, and highly efficient construction.

I accomplish these and other objects by means of the improved device disclosed in the drawings forming a part of the present invention wherein like characters of reference are used to designate similar parts throughout the specification and drawings, and in which:

Fig. 1 is a broken perspective view of my improved case as viewed from the front;

Fig. 2 is a horizontal section of the case showing a plan view of the refrigerating means and display rack;

Fig. 3 is a broken transverse section of the upper portion of the case;

Fig. 4 is a broken plan view of a refrigerating tank;

Fig. 5 is a longitudinal section of the tank as shown in Fig. 4; and

Fig. 6 is a broken back elevation of a portion of the tank showing a shutter mounted adjacent an air flue thereof.

Referring to the drawings, my invention comprises a show case consisting of a base 1 and an upper display portion 2. The case is constructed in any suitable manner from heat insulating materials, and the upper display portion is provided with a transparent front 3 extending the full length of the case. The upper back portion of the case is provided with suitable sliding doors 4 movable to afford access to the interior of the case. A floor 6 separates the base and upper portions of the case and forms the bottom to the upper display portion 2 of the case. The front and back walls of the upper portion preferably converge toward the top of the case and are joined across the top by a relatively narrow top portion 7.

A brine tank designated in general by the numeral 8 is mounted longitudinally within the upper display portion 2 of the case, preferably immediately above the floor 6 and at the back of said display portion 2, within a recess 9 formed below the doors 4. The back of the recess is closed by a door 11 hingedly mounted across the back of the case and arranged to swing downwardly to afford access to the tank 8.

The brine tank 8 is preferably formed in a single unit extending substantially the full length of the case, as indicated in the drawings. The tank 8 is formed from suitable sheet metal and is provided with a plurality of spaced air flues 12 mounted to extend transversely through the tank and opening through the front and back of the tank. A shutter 14 is mounted upon the back of the tank 8 adjacent each flue 12, the shutters 14 preferably being slidably mounted between guides 16 secured upon the back of the tank whereby the shutters may be moved independently to cover desired portions of the adjacent flues to limit the circulation of air therethrough.

A refrigerating coil 17 is mounted longitudinally within the tank 8. The coil 17 is connected at one end to an inlet connection 18 and at the opposite end to an outlet connection 19, said connections 18 and 19 being connected to a suitable refrigerating machine, not shown. The coil 17 consists of a plurality of spiral turns arranged in groups between adjacent flues 12, each group being connected to adjacent groups by portions 17' extending over the intermediate flue. Progressively increasing numbers of turns are formed in successive groups from the inlet to the outlet ends of the coil to provide progressively increasing length of coil in the groups of turns remote from the inlet, as disclosed in Fig. 5 of the drawings.

The tank 8 is provided with a cover 21 fitted onto the top of the tank and having a plurality of apertures 22 formed therein whereby moisture from brine contained within the tank may be absorbed by the air within the case to maintain the humidity of said air.

The tank 8 is supported upon suitable legs 23 supporting the tank above the floor 6 and spaced from the back and top of the recess 9 to permit a free circulation of air around the tank for the full length thereof.

A plurality of supports 24 are mounted upon the floor 6 of the case, said supports extending transversely of the case with the ends of the supports spaced from the front and back of the case. The supports are spaced longitudinally of the case, preferably midway between the flue passages 12 of the tank 8. A plurality of slats 26 are mounted in spaced parallel relation upon the supports to extend longitudinally from one end of the case to the other. The slats 26 are supported above the plane of the floor 6 and form a rack to support a plurality of display trays 27 for displaying meat or other products to be displayed. A slat 28 is mounted upon edge across the forward ends of the supports 24 to engage the forward edges of the trays 27 and hold said trays spaced from the front wall of the case. The upper edges of the supports 24 are prefer-

ably inclined downwardly from the back to the front of the case to support the trays 27 in an inclined position whereby products may be effectually displayed. The spaces between adjacent supports 24 afford unobstructed passages for air to circulate under and around the trays 27.

In operation, products, such as meat, fish, or other perishable goods to be displayed in a refrigerated atmosphere, are placed upon the trays 27 within the case whereby the products may be observed through the transparent front 3 which is preferably formed from three spaced panes of glass to prevent frosting of the glass.

The tank 8 is filled with brine to a level above the top of the coil 17 and cooled by the action of expanding liquefied gas within the coil in the well known manner, the gas being compressed and admitted into the coil 17 through a restricted orifice in the inlet connection 18 and the expansion of said liquefied gas within the coil operating to absorb heat from the surrounding brine and reduce the temperature to a desired degree. The ordinary concentrated calcium brine is used whereby the brine may be reduced to a very low temperature without freezing.

The liquefied gas expanding within the coil 17 absorbs heat rapidly as it expands through the first few turns of the coil adjacent the inlet so that the inlet end of the coil will be quickly reduced to a frosting temperature while the coils more remote from the inlet will be only slowly reduced in temperature. This results in a material variation in the temperature of the tank at the inlet and outlet ends thereof. I compensate for this variation by providing an increased number of turns of the coil as the distance from the inlet is increased, thus affording an increased area of coil and thereby increasing the absorption of heat from the brine proportionately. This results in increasing the speed with which the frost line is advanced along the tank from the inlet to the outlet ends thereof, when the refrigerating machine is first started, and insures a substantially uniform temperature along the full length of the tank after the desired temperature has been obtained.

For very long show cases, the single brine tank may be provided with longitudinally spaced coils having separate inlets and outlets, or two separate tanks and coils may be mounted in longitudinal alignment to further increase the rapidity with which the brine may be cooled and to further insure uniformity of temperature. As this modification is of an obvious nature, detailed illustration of this modification is omitted from the drawings.

As the temperature of the brine within the tank 8 is reduced, the air immediately surrounding the tank and particularly within the flues 12, becomes cooled and tends to move

5 toward the front of the case to displace the warmer and lighter air occupying the forward portion of the case. At the same time, the relatively warmer air within the top of the case is drawn downwardly onto the tank 8 and through the flues 12, thereby causing a circulation of air around the tank and through the flues 12, the cooled air moving forwardly under the trays 27 and around the products displayed thereon.

10 The circulation of air through the flues 12 is regulated by means of the shutters 14 to suit varying conditions. During cold seasons, and when the natural humidity of the air is high, a proper refrigerating of the products displayed is obtained by reducing the circulation of air within the case. This is accomplished by moving the shutters 14 to cover desired portions of the flues 12 and thus restricting the circulation of air therethrough.

15 The shutters are independently adjustable to permit a variation in the circulation within different portions of the case. This permits the flues 12 to be restricted to a greater degree at one end of the case than at the other to compensate for different conditions resulting from the fact that the doors 4 at one end of the case are usually opened more frequently than the doors at the opposite end. The hinged door 11 affords ready access to the tank 8 for cleaning in and around said tank and for adjusting the shutters 14. The door also permits the tank to be inserted and 20 removed as a unit when necessary.

25 While I have illustrated and described my invention in what I now regard as the preferred embodiment, the device is subject to modification in numerous details of construction and arrangement without departing from the spirit of my invention. I therefore desire to avail myself of all modifications which may fall within the scope of the appended claims.

30 Having thus described my invention, what I claim as new and desire to secure by Letters Patent is:—

35 1. A refrigerator show case comprising a case having a transparent front; a brine tank mounted longitudinally within the case; a plurality of air flues formed transversely through the tank; a refrigerating coil mounted within the tank to cool brine therein, said coil having progressively increasing numbers of turns between successive flues from the intake to the outlet end of the coil; and a display rack mounted within the case to support products to be displayed in spaced relation to the bottom and walls of the case 40 whereby air moving past the tank may circulate under and around said products.

45 2. A refrigerator show case comprising a case having a transparent front; a brine tank mounted longitudinally within the case; a plurality of air flues formed transversely

45 through the tank; a refrigerating coil mounted within the tank to cool brine therein, said coil having progressively increasing numbers of turns between successive flues from the intake to the outlet end of the coil; a display 50 rack mounted within the case to support products to be displayed in spaced relation to the bottom and walls of the case whereby air moving past the tank may circulate under and around said products; and shutters 55 mounted adjacent each air flue to regulate the circulation of air therethrough.

3. In a refrigerator show case, a brine tank mounted longitudinally of the case; a plurality of air flues mounted transversely through the tank; and a refrigerator coil mounted longitudinally within the tank and provided with progressively increasing numbers of turns between successive flues from the intake to the outlet ends of the coil.

4. In a refrigerator show case, a brine tank mounted longitudinally of the case; a plurality of air flues mounted transversely through the tank; a refrigerator coil mounted longitudinally within the tank and provided with progressively increasing numbers of turns between successive flues from the intake to the outlet ends of the coil; and shutters adjustably mounted adjacent each flue and independently operable to regulate the circulation of air through each flue.

In witness whereof, I hereunto set my signature.

JOSEPH WOOLF.
